FIG. 1 is a top perspective view of a tamper evident bottle cap, showing my new design;
FIG. 2 is a front elevational view thereof;

FIG. 3 is a rear elevational view thereof;

FIG. 4 is a top view thereof;

FIG. 5 is a bottom view thereof;

FIG. 6 is a front bottom perspective view thereof;

FIG. 7 is a rear bottom perspective view thereof;

FIG. 8 is a front elevational view thereof, shown in a position of use with an exemplary bottle;

FIG. 9 is a top perspective view thereof with a ring portion of the tamper evident bottle cap separated and retained on the bottle; and,

FIG. 10 is a front bottom perspective view thereof, with the exemplary bottle removed, showing the ring as separated from the cap.

(Continued)

The broken lines are shown for the purpose of illustrating environmental subject matter of an exemplary bottle and form no part of the claim.
